UNITED STATES PATENT OFFICE.

WILLIAM P. SOLOD, OF NEW YORK, N. Y.

CHECKERBOARD.

Application filed March 25, 1927. Serial No. 178,272.

My invention relates to checkerboards and particularly to folding checkerboards.

The invention has for its general object to provide a novel checker holding means incorporated in the board in a manner that the foldable sections of the checker board when in the folded position house the checkers and prevent loss of the same.

The nature of my invention and its distinguishing features and advantages will clearly appear as the description proceeds.

Reference is to be had to the accompanying drawings forming a part of this specification, it being understood that the drawings are merely illustrative of one example of the invention.

Figure 1 is a plan view of a checkerboard embodying my invention, showing the same in the unfolded position for playing.

Figure 2 is a transverse vertical section on the line 2—2 of Figure 1.

Figure 3 is a vertical section on an enlarged scale the section being taken on the line 2—2 as referred to and showing the board folded and the checkers housed.

In carrying out my invention in accordance with the illustrated example, a board is made in two folding half sections 10 united by any suitable hinge 11. At the opposite edge from the hinge any approved fastener means for the section may be provided, the means shown consisting of a short strip 12 having a fastener element 13 adapted to engage a mating fastener element 14 on the back of one of the sections 10.

Each half section 10 of the board is provided on three sides with a channel 15, the

adjacent ends of the channels being closed by members 16. The grooving or channeling of the boards at three sides provides for holding the checkers indicated at A in playing the game. When the sections are folded one on the other as shown in Figure 3 the channels jointly serve to house the checkers which are partly accommodated in the channel of one section and partly in the channel of the other section.

I would state furthermore that while the illustrated example constitutes a practical embodiment of my invention, I do not limit myself strictly to the exact details herein illustrated, since, manifestly, the same can be considerably varied without departure from the spirit of the invention as defined in the appended claim:

What I claim is:

A checkerboard formed of two hinged sections each having a playing field divided into a plurality of rows of spaces to receive men and intervening spaces, each of said sections on three sides of the playing field of said section having a channel extending continuously about said three sides for receiving checkers pertaining to the field of the section, the channel of one section being opposite the channel of the other and corresponding therewith, the two channels when the sections are folded one upon the other jointly forming a storage chamber, the channel of the each section partly accommodating the checkers and the two jointly accommodating all the checkers of the two fields in the single storage chamber.

WILLIAM P. SOLOD.
